AUTOMATIC SHUT-OFF FOR PRINTING PRESSES

John F. Banthin, Bridgeport, Conn.

Application May 25, 1948, Serial No. 29,013

13 Claims. (Cl. 101—278)

1

This invention relates to new and useful improvements in printing presses and has particular relation to means for instantly bringing to a stop movements of all parts of a press on the opening of the vacuum system including the vacuum suckers of the transfer or delivery mechanism of the press.

An object of the invention is to provide a means in a press having a delivery mechanism for delivering sheets or the like from a stack to an impression cylinder and which delivery mechanism includes vacuum suckers, means for instantly stopping the press on the opening of the vacuum system to atmospheric pressure whereby the press will be stopped should even one of the vacuum suckers be left exposed as, for example, if the piece of paper or other material to be printed upon is not being held by all of the vacuum suckers because one has released or one has not gripped the paper whereby the paper may be held in other than the proper manner.

Other objects and advantages of the invention will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

The present stop mechanism is herein disclosed as applied to a press of the general type disclosed in my prior application Serial Number 745,262 filed May 1, 1947, now Patent Number 2,592,998. However, it will be clear that the present invention claims are not specifically limited to the particular construction of press disclosed in said application since it is intended that the claims should cover the invention and all feasible applications on any construction of press.

In the drawings:

Fig. 1 is a side elevational view showing a printing press having the invention incorporated therein;

Fig. 2 is a side elevational view on a larger scale showing portions of the press to which the means of the invention is directly applied and with which the means of the invention directly operates;

Fig. 3 is a view on a larger scale and partly in side elevation and partly in vertical section showing the details of construction of my present mechanism;

Fig. 4 is a top plan view of the parts shown in Fig. 3 with the exception that the bed of the press is omitted; and

2

Fig. 5 is an isometric view illustrating the relation of said parts when the stop mechanism has been tripped.

Referring in detail to the drawings, at 10 is generally indicated a printing press and the same comprises a base or frame 11 which may be in the form of a single casting and generally rectangular in plan. Mounted on the frame 11, as by bracket or bearing means 12, is an impression cylinder 13 and operable below such impression cylinder in the usual manner is a type bed 14 adapted to be reciprocated in certain timed relation with vertical movements of the cylinder 13 as is customary in the art.

At 15 is shown a support for a stack of paper 16 and a paper feeding means or transfer mechanism generally designated 17 is designed for removing the sheets one at a time from the stack 16 and delivering such sheets to the impression cylinder 13. This transfer mechanism includes a pivoted arm 18 pivotally mounted as at 19 and designed to be rocked about said pivot in a path to have the transfer mechanism deliver a sheet from the stack 16 to the impression cylinder and to then have a return movement to pick up the next sheet from the stack, etc.

For the operation of the transfer mechanism 17, I have shown a crank arm 18a as an extension of the arm 18 and a link 18b pivoted at its respective ends to said crank arm and a rocker 18c serves to rock the transfer mechanism through the necessary movement. Rocker 18c is pivoted intermediate its ends as at 18d and mounts a roller 18e located in a groove 18f in a cam 18g on a shaft 18h also mounting a gear 18i meshing with a driving gear 18j on a shaft 18k. This mechanism is more fully described in my above identified application for patent.

Actually there are two of the arms 18 employed and between their upper ends they mount a manifold 20 from which flexible tubes or the like 21 connect with the vacuum suckers 22 commonly employed in the art. From a suitable source in a suction system, a suction or vacuum is applied to the manifold 20 and thence through the tubes 21 to the vacuum suckers 22. This suction is applied in certain timed relation with operations of the press, all as is usual in the art, and customarily the suction is on the suckers 22 when they are over the stack as in Fig. 1 whereby they pick up the top sheet of the stack.

Then, in the normal operation of this type of press, the transfer or feeding mechanism is swung forwardly about the pivots 19 until the suckers approach head stops 23 when the vacuum system is open to atmosphere whereby the suckers release the sheet against the head stops whereupon the

forward edges of the sheet are engaged by the grippers (not shown) of the impression cylinder. Thereafter, the return movement is applied to the transfer mechanism 17 and the suckers 22 are carried back to their loading position over the stack 16.

Suction to the vacuum suckers 22 originates in a vacuum pump 22a driven as by a motor 22b through pulleys 22c and a belt 22d. From the vacuum pump 22a, a pipe 22e connects with a T-fitting 22f one branch of which mounts a vacuum gage 22g while a tube or pipe 22h from its other branch leads to a control valve device 22i, as fully described in my copending application Serial Number 29,012 filed May 25, 1948. From such control valve device, a tubing 22j connects with an end of the manifold 20 for the application of a suction thereto.

At times the suckers may pick up a sheet of paper in a disarranged or inclined position whereby its forward edge is not straight across, or the suckers may drop the sheet part way to the head stops 23 or the like. Under such circumstances, the improperly placed sheet will probably get out of position in the press and later, particularly if there are several such sheets, they will become jammed about the impression cylinder and other adjacent parts and likely result in bending or distortion of some parts.

It will be understood in this connection that, prior to the present invention, if the suckers drop the sheet too soon or in improper alignment, the operation of the press will continue and the suckers of the transfer mechanism will continue to shift sheets from the pile or stack toward the impression cylinder. According to the present invention, means are provided whereby on opening of the vacuum system to atmospheric pressure, the press will be stopped almost instantly. Thus, in a press equipped with the present mechanism, should one of the suckers 22 be exposed, as it will be if a sheet is held at an angle or in improper alignment, the opening of the vacuum system to atmosphere through even one sucker will cause such a drop in the vacuum pressure that the present mechanism will go into operation and bring about substantially instant stopping of the press.

The operator or attendant will, of course, know that something is wrong and he can then remove the improperly placed or disarranged sheet and again start the press into operation. Thus, an accumulation of sheets in positions about the impression cylinder or adjacent parts will be prevented and in this connection it will be understood that when the press is stopped by the present mechanism and then again started, it will continue through the interrupted cycle so that its cycle of operation will be that for which the press was originally set.

On the near side of the press frame 11 there is mounted a control box 24, the power leads to which may run through the conduit 25 and from such control box a conduit 26 carries leads to a micro-switch 27, also mounted on such side of the press. Operation of this micro-switch by means to be described results in opening of a main switch or circuit breaker or the like within the control box 24 whereby the power to the press is cut off. The operating button of the micro-switch 27 is designated 28 and is shown as projecting toward the delivery end of the press. This particular location is a matter of convenience.

The main drive shaft of the press 10 is indicated at 29 and on said shaft is any or the usual flywheel 30 and also a drum 31. Shaft 29 and thus the flywheel 30 and the drum 31 are driven by a belt 30a from any suitable source of power and through a belt 32 passing about a small pulley 33 fast on the shaft 29 other parts of the press may be driven. Since the drive from the shaft 29 to the various parts of the press is old and well-known and conventional structure, it is not deemed necessary to confuse or enlarge the present disclosure by disclosing such means.

About the drum 31 a brake band 34 is located and the same is provided with any friction material 35 designed to be drawn against said drum for the purpose of braking the press. One end of this band 34 is suitably anchored as at 36 to a wall 37 of the frame 11 while the other end of the band is anchored as at 38 to an arm 39 of a lever generally designated 40. Intermediate its ends this lever is pivotally mounted at 41 and then the second arm 42 of the lever is carried upwardly and at its upper end is provided with a laterally extending lug portion 43, the purpose of which will appear. Also, at its upper end the lever may be provided with a projection or extension 44 constituting a hand piece for use in rocking the lever.

A coil spring 45 anchored to the frame wall 37 as at 46 has its other end anchored to a stud 47 rigid with the lever arm 42 toward the upper end of the latter. Clearly, the spring 45 is constantly tending to rock the lever 40 about the pivot 41 in a counterclockwise direction and in a direction to tighten the brake band 34 about the drum 31 to draw the friction pad or lining 35 into tight engagement with said drum whereby to provide a braking action for the whole press.

Pivotedly mounted on the wall 37 as by a stud 48 is a trigger device generally designated 49 and in side elevation generally of inverted T-formation. Thus, the trigger 49 comprises a generally vertical arm 50 comprising a stem of the T and a pair of oppositely extending generally horizontal arms 51 and 52 together comprising the head of the T. A short stud or shaft 53 on the trigger arm 52 mounts a roller 54 designed to engage and press inwardly on the operating stem or button 28 of the micro-switch 27 whereby to trip such switch, as will appear.

Trigger arm 51 is laterally thickened and enlarged on its inner side toward its free end and is provided with a notch 55 designed to substantially receive or receive a substantial part of the enlargement, projection or protuberance 43 at the upper end of the lever arm 42 when the trigger 49 is functioning to retain the lever 40 in a brake release position against the tendency of the spring 45 to move said lever to brake applied position.

Extending outwardly from the near side of the stem 50 of the trigger 49 is a short projection or stud 56 comprising a finger or hand piece for convenient use in manually rocking said trigger for the resetting of the press mechanism, all as will presently appear. On its inner side at its upper end, the trigger arm or stem 50 is laterally enlarged providing a shoulder or surface 57 designed to be engaged by a projection or pin 58 of a trip mechanism generally designated 59, at predetermined times, as will be set forth.

The trip mechanism 59 is more particularly shown or is better shown in Figs. 3 and 4. There it will be seen that such mechanism includes a bracket 60 secured to the side of the press 10 as

by bolts 61 passing through openings 62 in a thickened or pad-like portion 63 of said bracket. In addition to said pad-like portion, the bracket includes a forwardly extending elongated arm 64 and an upstanding rigid lug-like portion 65 at right angles to the arm 64 and located approximately at the juncture of said arm and the pad-like portion 63 of the bracket.

Toward its forward end, the bracket arm 64 mounts a stud 66 projecting from the near side of said arm and passing through a lever 67 intermediate the ends of said lever but in eccentric relation to the mid point of the lever. Thus, the stud 66 is located toward the forward end of the lever 67 so that said lever is overbalanced toward its rear end and its rear portion, or its portion to the right of the pivot 66 (Figs. 3 and 4) overbalances the lever portion toward the left of said pivot and therefore the lever under the influence of gravity constantly tends to move to and below the position shown in Fig. 3 in a clockwise direction or in a direction to carry its forward or shorter end portion upwardly.

Extending laterally from the near side of the forward end portion of the lever 67 are a pair of studs 68 and 69 and these studs pass through slots 70 and 71, respectively, in the elongated body portion 72 of a dog 73 which at its forward end is provided with an upstanding tooth 74 straight at its inner side whereby to provide a shoulder 75. The pin 58 above referred to is shown as extending entirely through the body 72 of the dog 73 and includes a portion 76 projecting at the inner side of the body. Anchored at one end to this portion 76 is a relatively heavy coil spring 77 which at its other end is anchored to a stud 78 projecting from the inner side of the lever 67.

Clearly, with this construction, spring 77 is constantly tending to close and therefore is constantly drawing inwardly on the dog 73 in a manner to bring the body portion 72 of said dog into overlapping relation with the forward end portion of the lever 67. Thus, the spring tends constantly to maintain the dog and the lever in such relation that the studs 68 and 69 are always in the forward end portions of the slots 70 and 71, respectively.

As will later appear, the trip mechanism 59 and particularly the dog 73 thereof cooperates with a plate 79 secured to the forward edge of the bed 14 as by bolts or the like 80 and includes a laterally extending and depending portion having an inner bevelled surface 81 and an outer straight surface 82. This construction is provided since it will be understood that during use of the press and in each cycle of the press' operation, the bed 14 is moved through a complete reciprocation. That is, it is moved first in one direction and then in the opposite direction under the cylinder 13.

As the bed moves toward the feeder end of the press, the bevelled surface 81 may ride over the bevelled surface of the tooth 74 as the latter is in position to permit of this and then under certain predetermined conditions, as will be described, as the bed moves in the opposite direction as the dog 73 is in the position shown best in Fig. 3, its shoulder 75 will be engaged by the straight surface 82 of the means 79 and the dog will be drawn forwardly a predetermined distance with the bed 14 to bring about movement of the trigger 49 and release of the lever 40.

A wing-like arm 83 is secured as by bolts 84 to the lug on an upstanding extension 65 of the bracket 60 and such wing serves to support a

body 85. This body 85 is provided with a cylindrical chamber 86 opening through its lower end and through a lateral orifice 87 communicating with a passageway 88 in turn communicating with a port or lateral opening 89 in which is threaded one end of a tube or pipe or nipple 90. Such tube or pipe or nipple 90 is through a piece of flexible tubing or the like 91 in communication with the manifold 20.

Extending through the lower open end of the chamber 86 is a cylindrical plunger 92 at its lower end provided with a bifurcated head 93 shown as straddling the longer end portion of the lever 67 and secured to such lever as by a cross pin 94 passing through the lever and the arms of the head 93. This pin 94 is rigid with the head 93 and passes through an elongated opening 95 in the lever 67 for certain relative movement of these parts, as will be made clear. In addition to the head 93, the plunger 92 includes a cylindrical portion 96 slidable in the chamber 86 and open at its inner end.

An adjusting screw 97 enters the chamber 86 through the upper end of the body 85 and within such chamber engages a sleeve 98, which sleeve is of a diameter to telescopically enter the inner or open upper end of the cylindrical portion 96 of plunger 92. Plunger 92 may be described as spring loaded since a coil spring 99 is located within such plunger and the inner portion of the sleeve 98 and at one end bears against a part of said sleeve and at its other end against the head 93 of the plunger. Clearly, this coil spring tends to project the plunger from the chamber 86 and to resist slight movement of the plunger into said chamber.

At its upper end, screw 97 is provided with a knurled head 100 for use in adjusting the screw and lock nut 101 is provided for securing the screw against casual movement relative to the body 85. This screw is adapted for adjustment to move the sleeve 98 longitudinally of the chamber 86 to vary the pressure of the spring 99 on the plunger head 93.

The bracket arm 64 is provided with an opening 102 and the longer arm of the lever 67 is provided with an opening 103. It will be clear that through the tube 91 the vacuum system connected with the vacuum suckers 22 is also connected with the chamber 86 and when vacuum is applied to this system and the same is closed to atmosphere, the suction resulting in the chamber 86 draws the plunger 92 inwardly of such chamber rocking the lever 67 as to the dotted line position of Fig. 3. In this position, the hole 103 aligns with the hole 102.

When setting up the press and timing it, the lever 67 may be manually rocked to this dotted line position and then a cotter pin or the like, as suggested at 104 in Fig. 4, is passed through the aligned holes to maintain the lever 67 and the dog 73 in the operating position while the press is being timed and is manually operated through its normal cycle. When the press is in use the cotter pin or the like 104 is removed from the openings 102 and 103. That is, this cotter pin is only used in set-ups or adjustments of the press to prevent the present stop means from acting while the press is being manually moved through its cycle for testing adjustments or set-up purposes.

In the operation of the press 10, the transfer mechanism 17, vacuum being present in the described system, when in the position of Fig. 1, through its suckers 22 takes the topmost sheet

from the stack 16. At this time, the impression cylinder 13 is in its upper or "off" position. Through conventional press mechanism, the transfer means is shifted and delivers this sheet to the head stops 23 to be engaged by the gripper buttons (not shown) of the impression cylinder 13.

At the time of this delivery, the vacuum system is open to atmosphere as by means disclosed in my above identified application breaking the suction on the suckers 22 whereby to release the sheet. As the transfer mechanism returns toward the stack, the cylinder 13 is lowered to "on" position and the bed 14 carries the type under the cylinder and into engagement with the sheet on the cylinder whereby the sheet is printed. This is all conventional structure.

At this time, the vacuum system is closed to atmosphere and so there is a suction through the manifold 20 and tube 91 and tube 90 to the chamber 86 and the plunger 92 is in its inner or upper position and the lever 67 is in the broken line position of Fig. 3 and the dog 73 is also in the broken line position of that figure. Thus, as the bed 14 moves, the member 79 will not strike the dog but will merely pass over it.

Now, on failure of the vacuum system as, for example, if one of the vacuum suckers 22 is exposed to the air because a sheet is not properly held or is not sealing such vacuum sucker, the vacuum fails in the chamber 86 and the plunger 92 moves downwardly and the lever 67 drops to the full line position of Fig. 3 carrying the dog 73 to the full line position of that figure. Now, as the bed 14 continues movement toward the left in Fig. 3, the surface 82 of the member 79 will engage the shoulder 75 of the tooth 74 of dog 73 and tend to move said dog toward the left.

Such movement of the dog is possible against the resistance of the spring 77 and results in some elongation of said spring. However, as the dog is so moved, it moves relative to the lever 67 since the latter is mounted on the stud or pivot 66 and is not capable of longitudinal movement. The slots 70 and 71 receiving the studs 68 and 69 permit of longitudinal movement of the dog 73 relative to the lever 67. However, it is noted that the slots 70 and 71 incline upwardly toward one another so that their inner or adjacent end portions are higher than their outer or remote end portions. Thus, as the dog 73 is moved by the member 79, the dog not only moves outwardly but its front or toothed end portion also must move downwardly. The pins and slots cause a cam-like action.

As the dog so starts to move, the pin or projection 58 of the dog is bearing against the shoulder or surface 57 of the stem 59 of the lever or trigger 49. Thus, this lever or trigger must rock in a counterclockwise direction. As it so rocks, its roller 54 swings upwardly and depresses the micro-switch actuator 28 opening the power circuit of the press by the tripping of a switch or circuit breaker or the like in the control box 24. This cuts off the power of the press.

Additionally, the described movement of the trigger 49 carries the shoulder or notch 55 of the outer end portion of its arm 51 downwardly releasing the lug or lateral extension 43 at the upper end of the arm 42 of lever 40. Immediately such lug 43 is released, the spring 45 rocks the lever 40 in a counterclockwise direction about the pivot 41 tightening the brake band 34 and drawing its frictional lining 35 tight against the drum 31 whereby a braking action is applied

to the power shaft 33. At this time, it will be understood that power has been cut off by interruption of the circuit to the primary motor and the application of the brake as described results in the whole press being rapidly brought to a standstill.

When the dog 73 reaches the broken line position of Fig. 3, it will be clear that the member 79 may now pass over the dog so there will be no damage to any part. Further, it will be clear that the pin 58 of the dog need only cause over-balancing of the trigger 49 to carry the notch 55 of the latter downwardly sufficient to release the extension 43 of the lever 40. Immediately this is done, the brake is applied and immediately prior to such operation, the roller 54 has actuated the control element 28 of the micro-switch. Thus, if the vacuum suckers are not all sealed by a sheet being transferred or if they are carrying no sheet, the press is stopped so that investigation may be made as to the trouble.

The transfer mechanism cannot be delivering sheets at an angle or the wrong way so as to clog up the press or cause other trouble. Unless the transfer means is operating properly, the vacuum in the vacuum system fails and the plunger 92 drops resulting in movement of the dog 73 to the full line position of Fig. 3 where such dog will be engaged by the member 79 and the entire trip mechanism 59 becomes effective to open the power circuit to the press and to immediately apply the braking mechanism described.

After the operator has remedied any defects, removed any misplaced sheet or the like, he draws the lever 40 to brake release position as by using the handle 44 and actuates the trigger 49 back to set position with its recess 55 receiving the lug or extension 43 of the lever 40 and with the surface 57 of said lever adjacent the pin 58. In this connection, it will be understood that immediately the press is tripped, the dog 73 has been moved to the broken line position of Fig. 3 and the narrow edge of the member 79 passed over the tooth 74 of the dog so the latter has been freed and has immediately returned to normal position awaiting the resetting of the trigger 49 and lever 40.

It will be understood that the present stop mechanism is quite rapid in its action and that it will serve to prevent the accumulation of misplaced sheets about the impression cylinder. The mechanism operates immediately anything happens to disrupt the vacuum system so that if the suckers have picked up a sheet without the sheet being properly aligned so that even one sucker is exposed, the plunger 92 is dropped and the tripping mechanism 59 set for the operation of the trigger 49 in the next forward movement of the bed 14. Thus, the present means does not permit of any error being repeated but stops the press practically at the start of an error and thus avoids damage to the press such as would result from an accumulation of errors.

Also, the present means operates to stop the machine without destroying the established cycle of operation of the press. Therefore, when any difficulty has been remedied, the operator merely resets the trigger 49 and brake lever 40, the press starts up at any place in its established cycle at which place it was stopped. Further, the present mechanism is effective to automatically stop operation of the press after the last sheet has been fed or transferred from the pile 16 to the impression cylinder. At such time when the suckers return to the feeder table, there is no

sheet for them to pick up or to seal them and thus the vacuum system is open to atmospheric pressure and the entire press is brought to a stand-still.

Having thus set forth the nature of my invention, what I claim is:

1. In a printing press including an impression cylinder, a transfer mechanism for transferring sheets from a pile to said cylinder, said transfer mechanism including a suction system, a bed reciprocable beneath said cylinder, a main drive shaft, a drum on and rotatable with said shaft, a brake band about said drum, a lever controlling tightening of said band about said drum to stop the same and said shaft, a spring normally urging said lever to position to tighten said band on said drum, a trigger device for retaining said lever in position against the tendency of said spring and with said brake band in released position, a control circuit for the driving of said press, and a micro-switch controlling said circuit and positioned for operation by said trigger as the latter is moved to release said lever for tightening of said brake band on said drum, a trip device on said press, means connected in said suction system and maintaining said trip device in inoperative position while said system is closed and releasing said trip device for movement to operative position on opening of said system to atmospheric pressure, and means on said bed and operative during movement of the latter in one direction to engage said trip device when the latter is in its last mentioned position and shift the same to operate said trigger to open said micro-switch and release said lever to permit movement of the latter by said spring to tighten said brake band on said drum whereby to bring said press to a stop.

2. In a printing press, a transfer mechanism including a suction system, a microswitch controlling the power circuit of said press, a brake actuating lever for applying a braking action to a given part of said press, a spring connected to said lever to move it in brake applying direction, a pivoted trigger having a contact part normally out of engagement with said microswitch and adapted upon movement of said trigger to engage and open said microswitch, and a retaining part normally engaged with said lever to retain it against the action of said spring in brake releasing position and adapted upon movement of said trigger to release said lever whereby it moves under the action of said spring to brake applying position, trip means on said press adapted to be shifted by a moving part of the press to pivotally move said trigger in a direction to open said microswitch and release said lever, and means connected in the vacuum system of the transfer mechanism of said press and serving to maintain said tripping means in an inoperative position while said vacuum system is under suction and is closed to atmosphere.

3. In a printing press including an impression cylinder and a bed horizontally reciprocable beneath said cylinder, said press comprising a transfer mechanism including a suction system for moving sheets from a pile to said cylinder, a microswitch controlling the power circuit of said press, means for applying a braking action to a given part of said press, a pivotally mounted trigger positioned for rocking movement to open said microswitch and normally maintaining said braking mechanism inoperative, a trip means, said trip means comprising a mounting bracket secured to said press, a lever eccentrically piv-

oted intermediate its ends to said bracket whereby the lever tends to rock about its pivot in one direction, a pair of studs extending from one side of the short end portion of said lever, a dog comprising an elongated body against said side of said end portion of said lever and extending beyond the outer end of said end portion of the lever and having an upstanding tooth on its portion beyond said end portion of the lever, said dog having a pair of slots through said body portion and through which said studs extend, a spring anchored at one end to said dog and at its other end to said lever and normally urging said dog toward side-by-side relation with said end portion of said lever whereby said dog is located with said studs in the forward ends of said respective slots, said slots inclining from their outer toward their inner or adjacent ends whereby said dog normally is held by said spring in a position with its toothed portion extending upwardly at an incline and whereby on said dog being moved forwardly relative to said lever and against the tendency of said spring said studs will be in the rear portions of the slots and said dog body portion will be substantially parallel with said lever, means connected in the vacuum system of the transfer mechanism of said press and serving to maintain said trip means in an inoperative position while said vacuum system is under suction and is closed to atmosphere and for releasing said trip means for movement to operative position on opening of said system to atmospheric pressure, and a part rigid with and reciprocable with said bed and operable during movement of the latter in one direction when said trip means is in operative position to engage said tooth and slide said dog against the tendency of said spring to engage and rock said trigger to open said microswitch and release said braking mechanism for braking action on said given part of the press.

4. In a printing press including an impression cylinder and a bed horizontally reciprocable beneath said cylinder, a transfer mechanism including a suction system, said transfer mechanism operable to transfer a sheet from a pile to said impression cylinder, a microswitch controlling the power circuit of said press, means for applying a braking action to a given part of said press, a pivotally mounted trigger positioned for rocking movement to open said microswitch and normally maintaining said braking mechanism inoperative, a tripping mechanism comprising a mounting bracket on said press, a lever pivotally mounted on said bracket intermediate the ends of the lever, a vacuum operated plunger connected with one end portion of the lever and adapted to maintain the latter in a predetermined inoperative position while vacuum is maintained in said suction system, a dog, means mounting said dog on the other end portion of said lever for movement therewith and for sliding movement relative thereto, said means mounting said dog for both a movement longitudinally of said lever and a movement downwardly with respect to said lever, rigid means on and reciprocable with said bed and positioned to engage and slide said dog to engage and rock said trigger to open said microswitch and release said braking mechanism for braking action on said given part of the press, and means connected in the vacuum system of the transfer mechanism and serving to maintain said tripping means including said dog in an inoperative position relative to said mov-

ing part of the press while said vacuum system is under suction and is closed to atmosphere.

5. In a printing press including an impression cylinder and a bed horizontally reciprocable beneath said cylinder, a transfer mechanism for transferring a sheet from a pile to said cylinder, said transfer mechanism including a suction system, a switch controlling the power circuit of said press, means for applying a braking action to a given part of said press, a pivotally mounted trigger positioned for rocking movement to open said switch and normally maintaining said braking mechanism inoperative, a tripping device for said trigger, said device including a mounting bracket secured on the press, a lever pivoted intermediate its ends to said bracket, a pair of studs extending from one side of an end portion of said lever, a dog comprising an elongated body against said side of said end portion of said lever and extending beyond the outer end of said end portion of the lever and having an upstanding tooth on its portion beyond said end portion of the lever, said dog having a pair of slots through said body portion and through which said studs extend, a spring anchored at one end to said dog and at its other end to said lever and normally urging said dog toward side-by-side relation with said end portion of said lever whereby said dog is located with said studs in the forward ends of said respective slots, said slots inclining from their outer toward their inner or adjacent ends whereby said dog normally is held by said spring in a position with its toothed portion extending upwardly at an incline and whereby on said dog being moved forwardly relative to said lever and against the tendency of said spring said studs will be in the rear portions of said slots and said dog body portion will be substantially parallel with said lever, said cylindrical recess connected in the vacuum system of said transfer mechanism whereby when said system is filled said plunger is drawn into said recess, said plunger when drawn into and held in said recess holding said lever in a position with said dog substantially horizontal, rigid means on and reciprocable with said bed and positioned to engage said tooth during movement of the bed in one direction and slide said dog in the direction of the lengths of said slots to engage and rock said trigger to open said switch and release said braking mechanism for braking action on said given part of the press, and means connected in the vacuum system of the transfer mechanism of said press and serving to maintain said tripping device including said dog and its tooth in an inoperative position with relation to said moving part of the press while said vacuum system is under suction and is closed to atmosphere.

6. In a printing press including an impression cylinder and a bed horizontally reciprocable beneath said cylinder, a transfer mechanism for transferring sheets from a pile to said cylinder, said transfer mechanism including a suction system, a switch controlling the power circuit of said press, means for applying a braking action to a given part of said press, a pivotally mounted trigger positioned for rocking movement to open said switch and normally maintaining said braking mechanism inoperative, a trip device including a mounting bracket secured on the press, a lever pivoted intermediate its ends to said bracket, a body on said bracket and having a cylindrical recess opening through its lower end, a plunger including a portion in said recess and a head at its lower end and connected with one end portion of said lever, a pair of studs extending from one side of the other end portion of said lever, a dog comprising an elongated body portion against said side of said end portion of said lever and extending beyond the outer end of said end portion of the lever and having an upstanding tooth

on its portion beyond said end portion of the lever, said dog having a pair of slots through said body portion and through which said studs extend, a spring anchored at one end to said dog and at its other end to said lever and normally urging said dog toward side-by-side relation with said end portion of said lever whereby said dog is located with said studs in the forward ends of said respective slots, said slots inclining from their outer toward their inner or adjacent ends whereby said dog normally is held by said spring in a position with its toothed portion extending upwardly at an incline and whereby on said dog being moved forwardly relative to said lever and against the tendency of said spring said studs will be in the rear portions of said slots and said dog body portion will be substantially parallel with said lever, said cylindrical recess connected in the vacuum system of said transfer mechanism whereby when said system is filled said plunger is drawn into said recess, said plunger when drawn into and held in said recess holding said lever in a position with said dog substantially horizontal, rigid means on and reciprocable with said bed and positioned to engage said tooth during movement of the bed in one direction and slide said dog in the direction of the lengths of said slots to engage and rock said trigger to open said switch and to release said braking mechanism for braking action on said given part of the press, and said plunger while in said recess and under the control of the suction of the suction system of the transfer mechanism of the press having an inoperative position with respect to said moving part of the press.

7. In a printing press including an impression cylinder and a bed horizontally reciprocable beneath said cylinder, a transfer mechanism for transferring sheets from a pile to said cylinder, said transfer mechanism including a suction system, a switch controlling the power circuit of said press, means for applying a braking action to a given part of said press, a pivotally mounted trigger positioned for rocking movement to open said switch and normally maintaining said braking mechanism inoperative, a trip device including a mounting bracket secured on said press, a lever pivoted intermediate its ends to said bracket, a body on said bracket and having a cylindrical recess opening through its lower end, a plunger including a portion in said recess and a head at its lower end and connected with one end portion of said lever, a pair of studs extending from one side of the other end portion of said lever, a dog comprising an elongated body portion against said side of said end portion of said lever and extending beyond the outer end of said end portion of the lever and having an upstanding tooth on its portion beyond said end portion of the lever, said dog having a pair of slots through said body portion and through which said studs extend, a spring anchored at one end to said dog and at its other end to said lever and normally urging said dog toward side-by-side relation with said end portion of said lever whereby said dog is located with said studs in the forward ends of said respective slots, said slots inclining from their outer toward their inner or adjacent ends whereby said dog normally is held by said spring in a position with its toothed portion extending upwardly at an incline and whereby on said dog being moved forwardly relative to said lever and against the tendency of said spring said studs will be in the rear portions of said slots and said dog body portion will be sub-

stantially parallel with said lever, said cylindrical recess connected in the suction system of said transfer mechanism whereby the suction in said system serves to draw said plunger into said recess, said plunger when drawn into and held in said recess adapted to hold said lever in a position with said dog substantially horizontal, spring means for moving said plunger outwardly of said cylindrical recess on failure of suction pressure in said suction system whereby to rock said lever on its pivot and move said dog to an inclined position, rigid means on and reciprocable with said bed and positioned to engage said tooth during movement of the bed in one direction and slide said dog in the direction of the lengths of said slots against the action of said spring to engage and rock said trigger to open said switch and release said braking mechanism for braking action on said given part of the press when said plunger is not held in said recess on movement of said plunger out of said cylindrical recess by the last mentioned spring on failure of suction pressure in said suction system.

8. In a printing press including an impression cylinder and a bed horizontally reciprocable beneath said cylinder, a transfer mechanism for transferring sheets from a pile to said cylinder, said transfer mechanism including a suction system, a switch controlling the power circuit of said press, means for applying a braking action to a given part of said press, a pivotally mounted trigger positioned for rocking movement to open said switch and normally maintaining said braking mechanism inoperative, a tripping mechanism comprising a mounting bracket secured on said press, a lever pivotally mounted on said bracket intermediate the ends of the lever, a vacuum operated plunger connected in said suction system and connected with one end portion of the lever and adapted to maintain the latter in a predetermined position while suction is maintained in said system, a dog, means mounting said dog on the other end portion of said lever for movement therewith and movement relative thereto, said means mounting said dog for both a sliding movement longitudinally of said lever and a movement downwardly with respect to said lever, said last means comprising a pair of studs projected from said lever and a pair of slots in said dog and inclining toward one another, rigid means on and reciprocable with said bed and positioned to engage said dog and slide the same in the direction of the lengths of said slots to engage and rock said trigger to open said switch and release said braking mechanism for braking action on said given part of the press, and said vacuum operated plunger connected in the suction system of said transfer mechanism whereby said tripping means is maintained in an inoperative position while said suction system is under suction.

9. In a printing press, a transfer mechanism including a suction system, a main drive shaft, a drum on and rotatable with said shaft, brake means for braking engagement with said drum, a lever controlling application of said brake means to said drum to stop the same and said shaft, a spring normally urging said lever to position applying said brake means to said drum, a trigger device having a contact part and a retaining part, said retaining part normally retaining said lever in position against the tendency of said spring and with said brake means in released relation to said drum and adapted to release said lever upon movement of said trigger device, a con-

trol circuit for the driving of said press, a switch controlling said circuit and positioned for operation by said contact part of said trigger as the latter is moved to release said lever for application of said brake means to said drum, a trip device on said press, means connected in said suction system and maintaining said trip device in inoperative position while said system is closed and releasing said trip device for movement to operative position on opening of said system to atmospheric pressure, said press including a movable part to engage said trip device when the latter is in its last mentioned position and shift the same to operate said trigger to open said switch and release said lever to permit of movement of the latter by said spring to apply said brake means to said drum whereby to bring said press to a stop.

10. In a printing press comprising a transfer mechanism including a suction system and an electrical power circuit, a switch in and controlling said circuit, means for applying a braking action to a part of said press, a spring normally urging said means to brake applying position, a trigger having three angularly related arms, means pivotally mounting said trigger in a position with one of its arms latching said brake applying means in released position against the tendency of said spring but for movement in one direction to release said means and with another arm positioned to open said switch on pivotal movement of the trigger in the mentioned direction, a trip device on said press, means connected in said suction system and maintaining said trip device in inoperative position while said system is closed and releasing said trip device for movement to operative position on opening of said system to atmospheric pressure, said press including a movable part to engage and shift said trip device when the latter is in said operative position, and said trigger having its third arm in the path of movement of said trip device when the latter is shifted by the moving part of the press whereby said trigger arm is engaged by said trip device and said trigger is rocked on its pivot to have its first mentioned arm engage and open said switch and its second mentioned arm release said brake applying means.

11. In a printing press including an impression cylinder, a transfer mechanism for transferring sheets from a pile to said cylinder, said transfer mechanism including a suction system, a frame, a bed reciprocable on said frame beneath said cylinder, power means, control means operable to control said power means whereby the press is started and stopped, trigger means for effecting the operation of said control means, and a trigger tripping mechanism comprising a lever pivotally mounted on said frame intermediate the ends of said lever, a vacuum operated plunger in communication with said suction system connected with one arm of said lever and adapted to draw said arm in one direction while vacuum is applied to said plunger whereby the other arm is moved in the opposite direction, lever actuating spring means arranged to move said lever in the opposite direction upon failure of the vacuum, a dog, means mounting said dog on said other arm of said lever for swinging movement therewith and for longitudinal movement thereon from a normal position, spring means exerting longitudinal force in one direction on said dog to return it to normal position from a longitudinally moved position, trigger actuating means on said dog arranged to move said trigger means in control

operating direction through longitudinal movement of said dog in opposition to said last mentioned spring means, a bed engaging part on said dog arranged to be contacted by a dog engaging part on said bed as the latter reciprocates in the direction of the trigger actuating direction of longitudinal movement of said dog, said part on said dog being out of the path of said part on said bed in the vacuum moved position of said lever and being moved into said path by said lever actuating spring means upon failure of said vacuum.

12. The invention as defined in claim 11 further characterized in that said means mounting said dog on said lever includes a cam slot connection whereby said dog has relative tilting movement on said lever as it is longitudinally moved thereon to disengage said dog and bed carried parts at one point in the longitudinal trigger actuating movement of the dog. 15

13. The invention as defined in claim 11 further characterized by cooperating cam parts on said

5 dog and bed for tilting said lever from its spring moved position in the path of said dog engaging part of said bed in opposition to said lever actuating spring means as said bed moves in opposite direction to the trigger operating direction of longitudinal movement of said dog.

JOHN F. BANTHIN.
